ANTI-TUMOR N-NITROSOMORPHOLINE
 Jean Bradley Harrison, Niagara Falls, N.Y., and Howard E. Hoffman, Wilmington, Del., assignors to E. I. du Pont de Nemours and Company, Wilmington, Del., a corporation of Delaware
 No Drawing. Filed Oct. 7, 1964, Ser. No. 402,320
 1 Claim. (Cl. 167—78)

This application is a continuation-in-part of our application Serial No. 265,373 filed March 15, 1963, now abandoned, which is a continuation-in-part of our now abandoned application Serial No. 156,157 filed November 30, 1961.

This invention relates to inhibition of tumor growth. More particularly it relates to inhibition of tumor growth using N-nitrosomorpholine.

According to this invention, N-nitrosomorpholine is an effective chemotherapeutic agent for the treatment of tumor growths. In laboratory tests on rats, intraperitoneal injections have been shown to delay or inhibit the regeneration of liver tissue surviving after a two-thirds partial hepatectomy. This activity is extremely rare in chemical compounds and is characteristic, for example, of N,N',N"-triethylenephosphoramide, an anti-tumor agent of merit in some cancer treatments.

The N-nitrosomorpholine will be administered in a tumor growth-inhibiting amount. Doses of from 0.1 to about 75 milligrams per kilogram of body weight of the recipient can be used as needed. Administration can be orally, intravenously, intraarterially, intraperitoneally, intracutaneously, subcutaneously, intramuscularly, by regional intraarterial infusion, percutaneously or interarticularly.

Our discovery of the anti-tumor activity of N-nitrosomorpholine is a highly useful and exciting research development. The compound has shown activity in mice against a variety of tumors. It has shown particularly high activity against the tumor Mecca lymphosarcoma. Other tumors that could be affected include malignant adenoma, hemangioendothelioma, adenocarcinoma, myeloma, epidermoid carcinoma, leukemia, bronchiogenic carcinoma, lymphosarcoma, malignant melanoma, reticulum cell sarcoma, retinoblastoma, leiomyosarcoma, osteogenic sarcoma, rhabdomyosarcoma, fibrosarcoma, teratoma, chondrosarcoma, endothelial sarcoma, lymphangioendothelioma, and liposarcoma.

The following examples are provided to more clearly define our invention.

Example 1

A daily dose of 30 milligrams per kilogram of body weight effects significant growth inhibition of the tumor Mecca lymphosarcoma in a host mouse. The dosage, tumor and host can be varied, as will be readily understood, without departing from the concept of the present invention.

Example 2

Sarcoma 180, ascitic form, was injected intraperitoneally into ten mice. The amount of tumor was approximately one million cells per mouse. Starting 24 hours after administration of the tumor cells, injection of N-nitrosomorpholine was made intraperitoneally once each day for seven days. At the end of ten days, the intraperitoneal fluid was removed and compared to the weight of the fluid in the control mice. The resultant data obtained from tests at two dose levels of N-nitrosomorpholine are given below.

2

Dose	Tumor T/C ¹ , gm.	Body Weight Change T/C ² , gm.	Deaths T/C ³
15 mg./kg.	4.0/7.9	+2.0/7.0	0/5
30 mg./kg.	4.6/9.3	-1.5/+800	2/5

¹ Ascites fluid: weight of fluid from treated mice/weight of fluid from control mice.

² Body weight change of treated mice/body weight change of controls.

³ Number of deaths of treated mice/number of deaths of controls.

This data indicates the compound N-nitrosomorpholine significantly inhibited the growth of the ascites tumor at 15 and 30 mg./kg.

Example 3

Uniform fragments of Wagner Osteogenic Sarcoma were implanted subcutaneously into the right axially region of ten mice. Five of these were injected intraperitoneally, starting twenty-four hours after implantation, with N-nitrosomorpholine dissolved in 0.85% NaCl. Treatment with the chemical continued for seven consecutive days, one injection per day. Five mice served as controls. During the course of therapy any unusual reactions in the host animals are recorded. At the start of the experiment and seven days after implantation of the tumor, the animals are individually weighed to detect possible weight loss which might suggest intoxication.

After two weeks each tumor in an experimental group was measured in situ by means of calipers through the largest apparent diameter and through a second diameter perpendicular to it. The average tumor diameter of the experimental group and of the control group were compared and the grading, weight change and deaths noted. The data obtained are as follows:

Dose	Tumor Size T/C, cm.	Body Weight Change T/C, gm.	Deaths T/C
30 mg./kg.	1.85/2.60	-3.5/+3.0	0/5

A significant inhibition of the tumor growth was observed.

Example 4

Using the Ehrlich carcinoma, an experiment as described in Example 3 was completed in a similar manner. The data obtained using the Ehrlich carcinoma are as follows:

Dose	Tumor Size T/C, cm.	Body Weight Change T/C, gm.	Deaths T/C
30 mg./kg.	1.85/2.60	-3.5/+3.0	0/5

A significant inhibition of the tumor growth was seen.

Example 5

Using the Lewis lung carcinoma, an experiment as described in Example 3 was completed in a similar manner. The data obtained using the Lewis lung carcinoma are as follows:

Dose	Tumor Size T/C, cm.	Body Weight Change T/C, gm.	Deaths T/C
30 mg./kg.	1.13/1.85	-3.0/+5.0	1/5

These data indicate that a significant inhibition in tumor growth was observed.

Example 6

Using the Mecca lymphosarcoma, an experiment as described in Example 3 was completed in a similar manner with one exception. The growth of the tumor was measured after three weeks. The data obtained using the Mecca lymphosarcoma are as follows:

Dose	Tumor Size T/C, cm.	Body Weight Change T/C, gm.	Deaths T/C
30 mg./kg.....	-.25/9.0	+2.3/+7.2	0/5

This data represents a highly significant inhibition of the Mecca lymphosarcoma.

The invention claimed is:

A method of inhibiting tumor growth in an animal comprising administering to said animal from about 0.1 to about 75 milligrams of N-nitrosomorpholine per kilogram of body weight of the recipient.
